UNITED STATES PATENT OFFICE

2,232,566

FUSE DEVICE

Jacob L. Shroyer, Oak Park, Ill., assignor to
Edison General Electric Appliance Company,
Inc., Chicago, Ill., a corporation of New York

Application June 10, 1939, Serial No. 278,504

11 Claims. (Cl. 200—133)

My invention relates to a fuse device and more particularly to a fuse device for electric appliances, such as electric ranges, and has for its primary object the provision of a simple, compact and inexpensive device which is constructed and arranged so that fuses may be removed without danger from shock or burning.

In general my invention relates to fuses of the so-called dead front type. Dead front fuse blocks have been constructed but in most instances these constructions have been relatively expensive to manufacture and somewhat bulky in construction. Since cost and space requirements are essential considerations in the manufacture of most electrical appliances and particularly electric ranges, these constructions have been impractical to use.

In accordance with my invention, I provide a fuse device of the dead front type which is inexpensive to manufacture, and is compact in construction. Specifically, I provide a fuse device which employs a standard fuse cut-out block. Constructed to cooperate with the standard cut-out block is a fuse holder block which is provided with a pair of brackets defining openings into which cartridge fuse elements are adapted to be inserted. Means are provided on the fuse holder block to hold the cartridge fuse elements in position and integral bosses are provided on the fuse holder block adjacent the brackets for positioning the fuse holder block relative to the cut-out block so that the cartridge fuse elements be properly aligned with respect to the contact clips on the cut-out block.

In its primary aspect, therefore, my invention contemplates the provision of a relatively inexpensive dead front fuse device which is readily adapted to be used in devices where space considerations are of paramount importance, such as electric appliances and particularly electric ranges.

In a more specific aspect, my invention contemplates the provision of a new and improved dead front fuse carrying block which may be employed with a standard cut-out block.

In another more specific aspect, my invention contemplates the provision of a fuse carrying block having integrally formed thereon means for supporting and carrying a cartridge type fuse.

In a further more specific aspect, my invention contemplates the provision of a molded fuse carrying block having integrally molded therewith a pair of brackets defining openings through which a cartridge fuse element may be inserted and also having means for holding the fuse element in its inserted position.

Further aspects of my invention will become apparent as the following description proceeds and the features which characterize my invention will be pointed out with particularity in the claims appended to and forming a part of this specification.

For a more complete understanding of my invention reference should be had to the accompanying drawings in which Fig. 1 represents a perspective view of my improved fuse device showing the standard fuse cut-out block with the fuse holder block mounted thereon; Fig. 2 represents a side view partly in section of the arrangement shown in Fig. 1; Fig. 3 represents a top view partly in section of the construction shown in Fig. 1; Fig. 4 is a rear view partly in section of my improved fuse carrying block showing the fuse cartridges in position; Fig. 5 is a front view of a modified form of my improved fuse carrying block; Fig. 6 is a rear view of the construction shown in Fig. 5; and Fig. 7 is a sectional view taken on the line 7—7 of Fig. 6.

Referring to Figs 1—4, my invention comprises a cut-out block 10. It is to be understood that this cut-out block 10 is a standard porcelain cut-out block which comprises a base portion 11 having side walls 12 and 13 and a central partition 14. Mounted in each of the channels formed between the partition 14 and the side walls 12 and 13 are substantially U-shaped clips 15 (Fig. 2) which are adapted to receive and firmly engage cartridge fuse elements 16. The U-shaped clips 15 are firmly attached to the base of the cut-out block 10 by means of rivets 17. Also provided in each of the channels formed in the cut-out block are terminal connectors 18 to which are adapted to be connected the leads 19 for connecting the fuse element in the circuit to be protected, for example, the electric circuit of a range or other electrical appliance. Screws 20 are adapted to extend through the base portion 11 of the cut-out block 10 so as to mount the block on some suitable supporting means indicated generally at 21. Provided centrally of the side walls 12 and 13 and the partition 14 and adjacent the top edge thereof are recesses 22 the purpose of which will be more fully described hereinafter.

The fuse element 16 may be of any suitable construction. The particular element illustrated (Fig. 4) is of the cartridge type having a cylindrical casing 23 of some suitable insulating material on each end of which is provided current carrying rings 24 which are adapted to be engaged by the clamps 15. Centrally arranged

in the cartridge element is a suitable fusible member 18. (Fig. 3).

In order to protect the user from the danger of electrical shock or burns when replacing the cartridge fuse elements, I have provided in accordance with my invention a new and improved fuse carrying member 26 which is adapted to be used with the standard fuse cut-out block described in detail above. In the form shown in Figs. 1-4, the fuse carrying block 26 is preferably molded from some suitable phenolic condensation product but it is to be understood that it may be formed from any suitable insulating material. The phenolic condensation product is preferred, however, because it is relatively light and readily molded in the desired form. Integrally formed on the block 26 and projecting from one side thereof is a pair of brackets 27 and 28 (Figs. 3 and 4) defining recesses through which the fuse elements 18 are adapted to be inserted and by which these elements are adapted to be carried when the block 26 is removed from the cut-out block 10. Integrally formed on the block 26 adjacent the brackets 27 and 28 are bosses 29 and lying between the brackets 27 and 28 is the integrally formed boss 30. These bosses are adapted to fit into the recesses 22 provided in the side walls 12 and 13 and the central partition 14 of the standard cut-out block 10.

Arranged to hold the fuse elements in position on the fuse block are lugs 31 and the spring clips 32. The lugs 31 are integrally formed on the block 26 and are adapted to serve as stops for positioning the cartridge elements centrally in the openings defined by the brackets 27 and 28. As illustrated in Fig. 4, these lugs are arranged on one side of the brackets 27 and 28 and are in substantial alignment with the opening defined by each of these brackets. The spring clips 32 are firmly secured to the block 26 by means of screws 33 and are arranged on the opposite side of brackets 27 and 28 in substantial alignment with the openings defined thereby. Each of the spring clips is provided with an upturned end portion 34 which is constructed and arranged to prevent movement of the cartridge member 18 out of the openings defined by the brackets. However, when the spring clip is pressed downwardly, the cartridge member may be withdrawn since the edge thereof will clear the upper edge of the upturned end portion 34. In the preferred embodiment of my invention, the lugs 31 and the spring clips 32 are arranged so as to loosely hold the cartridge elements in position relative to the fuse carrying block. This permits slight movement of the cartridge element which facilitates aligning and inserting the element in the contact clips 15. While this is a preferred arrangement, it is to be understood that the spring clip may be so arranged as to positively bias the cartridge element against the lugs 31 and thereby firmly hold the fuse element in position.

To facilitate the manipulation of the block 26, there is provided thereon a suitable handle 35 which comprises a ring 36 mounted in an eye bolt 37 which is firmly attached to the block.

While the manner in which my improved fuse device functions will be apparent from the foregoing detailed description, the salient points will be briefly discussed. Assuming that it is desired to repair or replace a fuse, the user will pull outwardly on the ring 36 thereby removing the fuse carrying block 26 from the cut-out block 10 and hence removing the fuses 18 from the contact clips 15. It will be observed that by means

of my improved construction the user's hands are remote from the electrical circuit being broken. The block 26, being of insulating material, produces a so-called dead front construction and removes any possibility of shock or burning of the user. With the fuse carrying block 26 removed from the cut-out block 10, the user may remove the cartridge element 18 which is to be repaired or replaced by pressing downwardly on the spring clip 32 so that the end of the element 18 clears the end portion 34 and at the same time pushing the cartridge element upwardly away from the lug 31 and out of the opening defined by either the bracket 27 or the bracket 28 as the case may be. The burned out fuse element may then be replaced in the cartridge or, if the cartridge is of the non-replaceable type, a new cartridge may be substituted therefor. The repaired or renewed cartridge is then inserted through the opening defined in the appropriate bracket until it engages the stop lug 31 and the spring clip 32 snaps in position so that the end portion 34 lies behind the adjacent end of the cartridge element 18.

With the fuse replaced the block 26 is inserted in the cut-out block 10. By means of the lugs 28 and 29 provided on the block 26, the fuse carrying block is guided into its proper relation with the cut-out block 10 so that the U-shaped contact clips 15 will engage the conducting portions 24 of the cartridge elements thereby completing the circuit from the terminals 16 through the fusible element 18.

In Figs. 5-7, I have illustrated a modified form of fuse supporting block for my improved fuse device. The block shown in these figures is similar in many respects to the form shown in Figs. 1-4. However, there are certain structural differences which will be described in detail below. It will be observed that the fuse carrying member comprises a block 38 which, like the block 26, is preferably molded from some suitable insulating material such as a phenolic condensation product. Provided on one side of this block is a suitable handle 39. Integrally formed on the opposite side of the block are brackets 40 and 41 which define substantially elongated recesses 42 and 43 which are adapted to receive the fuse elements (not shown). Also integrally formed on the block 38 adjacent the brackets 40 and 41 are the bosses 44 and 45 which, in a manner similar to the bosses 28 and 30 of the form of my invention shown in Figs. 1-4, serve to position the block 38 in a standard cut-out block. One of the essential differences between the modified form of block shown in Figs. 5-7 and the form of block shown in Figs. 1-4 is that openings 46 and 47 are provided in the front wall of the block opposite the brackets 40 and 41. These openings 46 and 47 serve as ventilating openings for cooling the fuse elements and also as windows through which the fuse elements may be observed when they are inserted in the recesses 42 and 43 defined by the brackets 40 and 41. As shown in Figs. 6 and 7, resilient clips 48 similar to the members 32 are firmly attached to the rear of the block 38 adjacent one side of the openings 42 and 43 defined by the brackets 40 and 41. In order to prevent the resilient clips 48 from twisting, slight recesses or depressions 49 are provided to receive the ends of the clips 48 which are attached to the block.

One other important difference between this modified form of my improved fuse carrying member over the form shown in Figs. 1-4 is that the

5 lugs for centering the fuse members within the openings 42 and 43 comprise a pair of circular lugs 50 which are integrally molded in the block. It was found that when the fuse carrying member 10 having a lug similar to that shown at 31, Fig. 4, was used with a standard double-pole double-branch type of cut-out block, it could only be inserted in its proper position when the end of the fuse carrying block having the lug thereon is adjacent the end of the cut-out block. If the fuse carrying block were inserted in the opposite direction, i. e. with the end of the block having the resilient clips 32 thereon adjacent the end of the cut-out block, a portion of the lug would engage 15 the central barrier provided in the standard double-pole double-branch cut-out block, thereby preventing the proper positioning of the fuse elements carried by the member 26. In order to overcome this difficulty, the cylindrical lugs 50 20 were provided and were made sufficiently small in diameter to permit the fuse carrying member or block 38 to be used in a double-pole double-branch construction irrespective of the manner in which it was applied thereto.

25 It is understood that the lugs 50 and the clips 48 cooperate to hold the fuse element in position on the block 44 and the clips permit insertion and removal of the fuse element.

30 From the foregoing detailed description, it is apparent that by means of my invention I have provided an improved fuse device which may be manufactured at low cost and which is relatively compact in construction. More specifically, I have provided a simple, inexpensive and compact 35 fuse carrying member which may be readily applied to a standard single-pole or double-pole cut-out block or to a double-pole double-branch cut-out block in order to produce a dead front fuse device which permits the manipulation of 40 the fuses without danger to the user from shock or burns. By means of the improved fuse carrying member, electrical appliances may be provided with dead front fuse devices and the space required for their application is not increased 45 over that required by the standard cut-out block used on such appliances.

50 While I have shown two particular embodiments of my invention, it will be understood, of course, that I do not wish to be limited thereto since many modifications may be made, and I, therefore, contemplate by the appended claims 55 to cover any such modifications as fall within the true spirit and scope of my invention.

55 What I claim as new and desire to secure by Letters Patent of the United States is:

1. In a fuse device of the dead front type, a 60 fuse carrying block, brackets on said block defining openings adapted to receive fuse elements, means on said block for longitudinally centering 65 said fuse elements relative to said openings defined by said brackets, means on said block for removably holding said fuse elements in said openings defined by said brackets, and means on said block adjacent said brackets for insuring the proper insertion of said fuse elements in their 70 circuit controlling position.

2. In a fuse device of the dead front type, a 75 fuse carrying block, brackets integrally formed on said block defining openings adapted to receive fuse elements of the cartridge type, latch means for holding said fuse elements in a central position relative to said openings defined by said brackets, and integrally formed bosses on said fuse carrying block adjacent said brackets arranged to cooperate with recesses in a cut-out

block to insure the proper insertion of said fuse elements in their circuit controlling positions.

3. In a fuse device of the dead front type, a 10 fuse carrying block, a bracket on said block defining an opening adapted to receive a fuse element, means on one side of said bracket and in substantial alignment with said opening defined thereby adapted to serve as a stop for said fuse element when the latter is inserted through said opening, resilient means provided on the side of 15 said bracket remote from said first mentioned means and adapted to cooperate with said first mentioned means to hold said fuse element in position, and means on said block adjacent said bracket for insuring the proper insertion of said 20 fuse element in its circuit controlling position.

4. In a fuse device of the dead front type, a 25 molded fuse carrying block, handle means on one side of said block, integrally molded fuse carrying brackets mounted on the opposite side of said 30 block, said brackets defining openings adapted to receive fuse elements of the cartridge type, means on said block for longitudinally centering said fuse elements relative to said brackets, resilient means arranged to cooperate with said centering means to loosely hold said elements in said 35 openings defined by said brackets, and means integrally molded on said block adjacent said brackets adapted to position said fuse carrying block relative to a cut-out block to insure the 40 proper positioning of said cartridge elements in the circuit to be protected.

5. In a fuse device of the dead front type, a 45 molded fuse carrying block, a fuse carrying bracket integrally molded on one side of said block, said bracket defining a recess adapted to receive a fuse element, a lug on said block for centering said fuse element relative to said bracket, resilient means on said block for holding said element against said lug, and bosses 50 integrally molded on said block adjacent said bracket for positioning said fuse carrying block relative to a cut-out block to insure the proper positioning of said fuse element in the circuit to be protected.

6. In a fuse device, a fuse carrying block 55 formed of molded insulating material, a pair of brackets molded on said block defining openings adapted to receive fuse elements, a pair of lugs molded on said block on one side of said brackets 60 and in substantial alignment with said openings defined by said brackets and adapted to serve as stops for said fuse elements when the latter are inserted through said openings defined by said brackets, spring clips attached to said block 65 on the side of said brackets remote from said lugs adapted to removably hold said fuse elements in position, and bosses integrally molded on said block adjacent said brackets adapted to cooperate with recesses in a cut-out block to insure 70 proper positioning of said fuse elements relative to the circuit to be protected thereby.

7. In a fuse device of the dead front type, a 75 fuse carrying block, brackets on said block defining openings adapted to receive fuse elements of the cartridge type, means for removably holding said fuse elements in said openings defined by said brackets, bosses on said block adjacent said brackets for positioning said block relative to a cut-out block, and walls defining a pair of openings in said fuse carrying block opposite said brackets to ventilate and cool said fuse elements.

8. In a fuse device of the dead front type, a 80 molded fuse carrying block, brackets integrally formed on said block, said brackets defining sub- 85

- stantially U-shaped recesses adapted to receive fuse elements, walls defining openings in said fuse carrying block opposite said brackets, said openings serving to ventilate said fuse elements when inserted in said recesses defined by said brackets and also forming windows through which said fuse elements may be inspected, lugs on said block on one side of said brackets and in substantial alignment with said recesses formed thereby for limiting the movement of said fuse elements into said recesses in one direction relative to said brackets, resilient means on said block on the opposite side of said brackets adapted to cooperate with said lugs to removably hold said fuse elements in said recesses, and bosses integrally molded on said block adjacent said brackets for positioning said block in a cut-out block to insure the proper positioning of said fuse elements relative to the circuits to be protected thereby.
5. In a fuse mechanism, a cut-out block having a plurality of vertically extending walls defining a plurality of passageways, each of said walls having a recess located centrally of the top edge thereof, contact means in each of said passageways adapted to receive a fuse element, a fuse carrying block, brackets on said block defining openings adapted to receive fuse elements, means on said block at one side of said brackets to limit the movement of said elements through said openings defined by said brackets, resilient means for loosely holding said elements in said openings, and means on said block adjacent said brackets adapted to cooperate with said recesses in said walls of said cut-out block to position said fuse carrying block and insure the proper mounting of said fuse elements in said contact means.
10. In a fuse mechanism, a cut-out block hav-
- ing a plurality of vertically extending walls defining a pair of passageways, said walls having recesses provided centrally of the top edge thereof, a pair of substantially U-shaped contact clips arranged in said passageways, a fuse carrying block 5 of molded insulating material, a pair of brackets molded on said block defining a pair of openings adapted to receive fuse elements of the cartridge type, lugs molded on said block at one side of said brackets to limit the movement of said fuse elements through said openings defined by said brackets and to center said elements longitudinally in said openings, spring clips secured to said block adjacent the side of said brackets remote from said lugs and cooperating with said lugs to 15 loosely hold said fuse elements in said openings, bosses integrally molded on said block adjacent said brackets adapted to cooperate with said recesses in said walls of said cut-out block to position said fuse carrying block and to insure proper 20 mounting of said fuse elements in said contact clips, and a handle firmly attached to said fuse carrying block to facilitate the insertion and removal thereof from said cut-out block.
11. In a fuse device of the dead front type, a 25 fuse carrying block, a bracket on said block defining an opening adapted to receive a fuse element, a stop on one side of said bracket for longitudinally centering said fuse element relative to said bracket when said fuse element is inserted 30 through said opening, latch means on the opposite side of said bracket for loosely holding said fuse element in position in said opening, and means on said block for insuring the proper insertion of said fuse element in its circuit controlling position.
- 35

JACOB L. SHROYER.

CERTIFICATE OF CORRECTION.

Patent No. 2,232,566.

February 18, 1941.

JACOB L. SHROYER.

It is hereby certified that error appears in the printed specification of the above numbered patent requiring correction as follows: Page 1, second column, line 23, for "Figs" read --Figs.--; page 2, first column, line 67, for the word "may" read --my--; page 4, first column, line 5, claim 8, for "recessse" read --recesses--; and that the said Letters Patent should be read with this correction therein that the same may conform to the record of the case in the Patent Office.

Signed and sealed this 25th day of March, A. D. 1941.

Henry Van Arsdale,

Acting Commissioner of Patents.
